ATTORNEYS

UNITED STATES PATENT OFFICE.

GEORGE WASHINGTON DOWNS, OF NEW YORK, N. Y.

SANITARY TELEPHONE ATTACHMENT.

1,066,388.

Specification of Letters Patent.

Patented July 1, 1913.

Application filed October 31, 1912. Serial No. 728,834.

To all whom it may concern:

Be it known that I, GEORGE W. DOWNS, a citizen of the United States, and a resident of the city of New York, borough of Manhattan, in the county and State of New York, have invented a new and Improved Sanitary Telephone Attachment, of which the following is a full, clear, and exact description.

10 This invention relates to telephony and has particular reference to means for safeguarding a user of an ordinary telephone from infection or disease which is likely to be transmitted to his lips by contact with 15 a public telephone mouthpiece.

Among the objects of the invention is to provide an attachment of the character set forth which may be of a simple and cheap nature and hence may be easily applied to 20 the ordinary form of telephone mouthpiece and used by any individual or in the case of a public telephone such attachment may be carried in one's pocket and easily applied and removed after being used, either 25 to be discarded or returned to the pocket for subsequent use.

A further object of the invention is to improve this sort of devices in such a way as to render them cheaper and therefore 30 more readily accessible for use as required and also to provide a device which may be more reliable in its coöperation with the mouthpiece.

The foregoing and other objects of the 35 invention will hereinafter be more fully described and claimed and illustrated in the drawings accompanying this specification in which like characters of reference indicate corresponding parts in all the views, and in 40 which—

Figure 1 represents a face view of one form of this invention; Fig. 2 is a vertical sectional view of the same applied to a telephone; Fig. 3 is a face view of a blank 45 for the formation of a modification of the invention; Fig. 4 is a face view of such modification complete; Fig. 5 is an edge view of the same looking toward the right in Fig. 4; Fig. 6 is a further modification 50 embodying the same principles as the other forms; Fig. 7 is a vertical sectional view on the line 7—7 of Fig. 6; and Figs. 8 and

9 are front and edge views respectively of a still further modification.

Referring more particularly to the drawings it is to be noted that in all forms of this invention the attachment is designed to be made of a single strip of any suitable sheet material and so slitted, stamped or formed as to provide a substantially stiff or rigid body portion of any suitable form or size, a tongue free and preferably rounded at one end and connected at its other end to the body, and a hanger adjacent the tongue and including a pair of comparatively narrow and hence flexible straps through which the hanger is connected to the body, all of said parts being integral when the attachment is made of a single strip of material.

The material may be cardboard, paper, celluloid or any other suitable fibrous or plastic material. The attachment, therefore, may be produced in large quantities very cheaply, or if it is to be made of a more permanent nature the material may be accordingly more expensive. The primary object, however, in this regard is to produce them so cheaply as to bring them within the use of every telephone user or operator. It is to be noted furthermore that the attachment may be of such a nature as to render it an excellent medium for advertising purposes, the advertisement to be printed or otherwise arranged upon the face thereof where it may be conspicuous when the person is about to use the telephone.

Referring more particularly to Figs. 1 and 2, it will be noted that the strip of material comprises a pendant body portion 10 shown as substantially rectangular in form and so slitted at 11 as to provide an opening, the upper portion of which is preferably circular and of such a size as to receive the mouthpiece of an ordinary telephone. 95 That portion of the strip of material surrounding the opening 11 constitutes what may be termed a "hanger" 12 which includes a pair of straps 13 whereby the hanger is connected to or made integral with the body portion 10. The straps 13 being comparatively narrow, they will be relatively flexible, making it easy for the hanger to be pressed back at its top for engagement

with the upper edge or lip *a* of the mouthpiece. It is to be noted furthermore that the hanger is continuous from one strap to the other whereby it is sufficiently strong for its purpose and well adapted for supporting the attachment in place upon the mouthpiece. This device also includes an upwardly projecting tongue 14 formed simultaneously with the cutting of the slit 10 forming the opening 11 above described. The base 15 of the tongue opposite its rounded free end 16 is therefore integral with the upper portion of the body 10 when the device is made from a single strip of material. The invention in this form, therefore, may be made very cheaply and put out as attractive souvenirs. It is possible, therefore, to supply any suitable number of them for any telephone which is used repeatedly by the public or different individuals. A person about to use the telephone may take one of these cards or devices and apply it to the telephone mouthpiece in the manner set forth, the position thereof being such that the tongue 14 will substantially cover or guard the usually exposed edge or lip of the mouthpiece, keeping the same from contaminating the person or user of the telephone.

I have found by a series of experiments of considerable extent that the tongue of such an attachment may be of comparatively thick or stiff nature without materially affecting the acoustic properties of the instrument, especially when one's mouth is placed directly in front thereof. If desired, however, the tongue 14 may be provided with a series of perforations which will more freely transmit the sound vibrations of the voice and yet will not detract from the sanitary nature of the attachment.

Figs. 3, 4 and 5 illustrate a slightly modified form of the invention in which the strip of material is preferably a little longer than that previously described and in the cutting of the blank there is formed an opening 11' for the reception of the mouthpiece as before, and this opening is surrounded by a hanger 12 having the same character of straps 13 as before described. The tongue 14', however, is formed below the opening 11' by slits 17, and the portions of the blank adjacent the slits 17 may be shortened in any suitable manner, hence, as shown, are folded, each twice upon itself substantially on the lines 18 and 19, the parts 20 being folded upon the outer face of the portions 21 to which the lower ends of the straps are connected. The body portion 10' is bent downwardly on the line 19 and up a the original rear faces of the parts 20. By virtue of the slits 17, however, the tongue 14' will remain in its original position with respect to the body 10' and will occupy a

place directly over the opening 11' and 65 preferably such tongue should be slightly longer than said opening so as to more thoroughly guard or protect the mouthpiece from contaminating tendencies. The parts folded as described and shown in Fig. 5 may-70 be loose or positively secured in permanent position. As in the other form of the invention, however, the tongue will still be of a single thickness of material and the same is true also of the hanger which should be 75 made of a comparatively flexible nature for easy coöperation with the mouthpiece.

Figs. 6 and 7 show another form of the invention made from a single blank and so stamped as to provide an opening 11'' and 80 hanger 12 having characteristics identical with those already described. The body portion 10'' in this form of the invention is produced by bending a portion of the strip upon itself along the line 18', such lower 85 portion when bent up constituting the tongue 14'' and conforming to the aforesaid opening 11''. The two parts of the body thus formed may be gummed together, making a relatively rigid body but leaving 90 the tongue and hanger portions each of single thickness and comparatively thin and flexible as in the other forms.

In the form of the invention shown in Figs. 8 and 9, each side edge of the device 95 is provided with an inwardly projecting transverse slot 22 into or through which the folded end 18' of the strap is projected for the purpose of maintaining the parts folded and substantially in the position in which they are intended to operate. By virtue of this construction it is possible to make a device of the character herein described, of thin paper and maintain the proper form without depending upon any special fastening means for the straps. 105

Having thus described my invention, I claim as new and desire to secure by Letters Patent;

1. The herein described sanitary telephone attachment comprising a relatively stiff pendant body portion, an upwardly projecting tongue integral at one end with the body portion, and a continuous supporting hanger adjacent the tongue, said hanger 115 including a pair of flexible straps adjacent the base of the tongue and formed integral with the body portion, substantially as set forth.

2. The herein described sanitary telephone attachment comprising a single strip of cheap sheet material so formed as to provide and include a relatively stiff body portion, the strip adjacent the body portion being provided with an opening to receive 125 the telephone mouthpiece, the strip surrounding the opening being continuous and constituting a hanger including a pair of

flexible straps connected to the body portion, and an upwardly projecting tongue conforming to said opening and adapted to guard the mouthpiece embraced by the hanger, said straps being shortened to cause the hanger to extend downward in the rear of the upper free end of the tongue.

In testimony whereof I have signed my name to this specification in the presence of two subscribing witnesses.

GEORGE WASHINGTON DOWNS.
